UNITED STATES PATENT OFFICE.

PERRY B. SAMPLES, OF HUNTINGTON, WEST VIRGINIA.

ROTARY VALVE.

1,176,857.

Specification of Letters Patent. Patented Mar. 28, 1916.

Application filed December 3, 1913. Serial No. 804,547.

To all whom it may concern:

Be it known that I, PERRY B. SAMPLES, a citizen of the United States, residing at Huntington, in the county of Cabell and State of West Virginia, have invented new and useful Improvements in Rotary Valves, of which the following is a specification.

This invention relates to improvements in rotary valves, especially designed for use in connection with explosive engines, for the purpose of controlling the admission and retention of the charge and the exhausting spent gases at proper predetermined intervals.

15 A further object of the invention is to provide a rotary valve which will perform the required functions of admitting the charge, retaining the same during the explosion, and permitting of the exhaust of the 20 spent gases, and which will perform these several functions in an accurately timed manner and without setting up any undesirable resistance to the inlet of the fuel charge or outlet of the exhaust gases.

25 A further object of the invention is to provide a valve of the character described, together with a novel construction of valve casing and arrangement of ports and passages, whereby efficiency of action is insured 30 without the necessity of making the valve of excess diameter.

The invention consists of the features of construction, combination and arrangement of parts herein fully described and claimed, 35 reference being had to the accompanying drawings in which:—

Figure 1 is a side elevation, with the valve casing shown in longitudinal section, of a two-cylinder engine embodying my invention. Figs. 2, 3, 4 and 5 are transverse sections taken on a line through one of the engine cylinders and showing the positions of the parts at different points in the cycle of operation of the engine. Fig. 6 is a vertical transverse section through the valve casing, valve and upper portion of the cylinder on an enlarged scale. Fig. 7 is a view of the valve *per se*, as designed for use on a two-cylinder engine.

50 Referring to the drawings, 1 designates an engine cylinder, 2 the piston operating therein, 3 the upper cylinder head, 4 the valve casing, and 5 the rotary valve.

55 In the following description, I have set forth the construction as relating to a single engine cylinder, but it will be understood

and observed that the features specified are duplicated in a two-cylinder engine of the character disclosed.

In Figs. 2, 3, 4 and 5 I have shown, respectively, the relative positions of the piston, valve, and inlet and exhaust ports, at the beginning of the exhaust, intake, compression and power stages in the cycle of operation of the engine.

60 The valve casing 4 is formed to provide an inclosed chamber 6 in which the valve 5 is mounted for rotation, and in practice the valve is driven at one-fourth the rate of speed of the engine shaft. The gearing for 65 rotating the valve may be of any preferred construction, but in the present instance I have shown the use of a valve actuating shaft 7 connected with the engine shaft 8 by 1-4 beveled gears 9 and with the valve 70 shaft 10 by 1-1 beveled gears 11.

75 The casing 4 is provided at diametrically opposite sides with an inlet port 12 and an exhaust port 13, which communicate respectively with pockets 12' and 13' formed in 80 said casing, while the upper cylinder head 3 is provided with inlet and exhaust ports 14 and 15 communicating with pockets 14' and 15' formed in the casing. The chamber 6 is provided with a pair of inlet ports 12^a 85 and 14^a, communicating with the respective pockets 12' and 14', and with a pair of exhaust ports 13^a and 15^a, communicating respectively with the pockets 13' and 15'. These sets of ports are adapted to be properly 90 connected during the course of rotation of the valve 5 to perform the several 95 functions before described.

As shown, the valve 5 is mounted to rotate snugly within the chamber 6 and is 100 suitably journaled upon the valve casing, and said valve is provided with a single combined admission and exhaust port 16 extending diametrically therethrough, which port is preferably of a width equivalent to one-sixteenth the circumference of the valve. In practice, the ports in the valve casing and valve are made relatively narrower and longer than the ports in the cylinder head, so as to provide for a free flow of the fuel 105 and gases without making the valve of excess diameter. The valve is adapted in its course of rotation, to connect the ports 13^a and 15^a for the exhaust of the burned gases from the cylinder, and to connect the ports 12^a and 14^a for the supply of the fuel charge 11 to the cylinder, and to occupy intermediate

positions during the compression and power stages of action. Fig. 2 shows the relative positions of the ports and passages at the beginning of the exhaust, Fig. 3 the positions of the ports and passages at the beginning of the intake, Fig. 4 the position of the valve during the compression stroke of the piston, and Fig. 5 the position of the valve during the power stroke of the piston, from which it will be seen that the valve in its cycle of rotation is adapted to admit a charge of fuel to the engine, hold the same retained during the compression stroke of the piston, firing of the charge and insuring power stroke of the piston, and to finally permit of the discharge of the spent gases, after which the cycle of operation above described is repeated. By the described arrangement of the ports and pockets in the valve casing and chamber, ease of flow of the entering charge mixture and discharging spent gases is insured, and at the same time such arrangement of the ports and pockets permits of the valve being rotated at a comparatively low speed, insuring an efficiency of operation not possible with rotary valves which require to be operated at a high speed in order to properly connect the ports during the cycle of action of the engine.

30 I claim:—

In a rotary valve mechanism for explo-

sive engines, the combination of an engine cylinder having separate and independent supply and exhaust ports, a valve casing formed to provide a circular valve chamber having an inner set of ports communicating with said inlet and exhaust ports of the cylinder, and also having an outer set of ports, the said valve casing being provided with supply and exhaust compartments partitioned from each other and communicating with the outer set of ports, said compartments being provided with inlet and exhaust ports, pockets upon the outer sides of the casing communicating with the last-named ports, said pockets being constructed for coöperation with suitable supply and exhaust connections, and a rotary valve arranged in said circular valve chamber and having a diametrically extending port adapted for coöperation with the sets of ports in said valve chamber, the ports in the casing, chamber and valve being relatively longer and narrower than the ports in the cylinder, and gearing for rotating said valve from the engine shaft.

In testimony whereof I affix my signature in presence of two witnesses.
